STEAM GENERATOR

Dana H. N. Mayo, Ridgewood, N. J., and Arthur E. Raynor, Rockville Centre, N. Y., assignors to The Babcock & Wilcox Company, Newark, N. J., a corporation of New Jersey

Application July 16, 1938, Serial No. 219,562

13 Claims. (Cl. 122—235)

The present invention relates in general to improvements in the construction and operation of steam generators of the type including convection heated steam heating surface and provisions for regulably by-passing heating gases around the steam heating surface to control the heat absorption thereof, and more particularly to steam generators of the Babcock & Wilcox high head type in which the convection heated steam heating surface and by-pass provisions are located in the space above an inclined bank of steam generating tubes and associated with auxiliary water heating, i. e. economizer surface.

The main object of the invention is the provision of an improved arrangement and construction of the economizer in a steam generator of the character described which is characterized by the simplicity and effectiveness of the economizer surface supporting provisions, the accessibility of the economizer surface for renewal and inspection, the protection of the by-pass control parts from overheating, and the high thermal efficiency of the steam generator unit with the by-pass in or out of use.

The various features of novelty which characterize the invention are pointed out with particularity in the claims annexed to and forming a part of this specification. For a better understanding of the invention, its operating advantages and specific objects attained by its use, reference should be had to the accompanying drawings and descriptive matter in which we have illustrated and described a preferred embodiment of the invention.

Of the drawings:

Fig. 1 is a partly diagrammatic sectional elevation of a steam generating unit incorporating the invention;

Fig. 2 is an enlarged view of an upper portion of the unit shown in Fig. 1;

Fig. 3 is a vertical section taken one the line 3—3 of Fig. 2;

Fig. 4 is an enlarged view of a detail of Fig. 3;

Fig. 5 is a section taken on the line 5—5 of Fig. 4;

Fig. 6 is an enlarged view of the economizer tube end support shown in Fig. 3;

Fig. 7 is a plan view of the structure shown in Fig. 6;

Fig. 8 is a vertical section taken on the line 8—8 of Fig. 6;

Fig. 9 is a vertical section taken on the line 9—9 of Fig. 2;

Fig. 10 is an enlarged view of a portion of Fig. 2; and

Fig. 11 is a vertical section taken on the line 11—11 of Fig. 10.

In the drawings the invention is illustrated as incorporated in a steam generator of the Babcock & Wilcox high head type comprising a two-stage pulverized coal burning furnace having a primary section 10 and a secondary section 11. The primary furnace section 10 is defined by fully studded tube walls designed for the maintenance therein of a normal mean furnace temperature above the ash fusion temperature of the coal used. A plurality of pulverized coal burning nozzles 12 are arranged to downwardly discharge through the arch 13 of the primary section. A water cooled floor 14 is constructed to collect and support a layer of molten slag in the primary section 10 which is withdrawable therefrom through a slag tap opening 15 in one of the side walls adjacent the floor level. The primary furnace section is partly separated from the secondary section by a fluid cooled partition 16 formed by refractory covered fully studded water tubes having their lower portions bent out of the plane of the tube row to form a series of transversely spaced gas passages 17 connecting the primary and secondary furnace sections.

The secondary furnace section 11 is of considerably greater height and volume than the primary section and also entirely water cooled. The lower portions of these side wall tubes are fully studded as in the primary section, but the upper portions and the remaining walls are covered by metallic blocks of the Bailey type to provide smooth wall surfaces having a high rate of heat absorption and designed to reduce the gas temperature therein to a value at the top exit below the fuel ash fusion temperature largely by gaseous radiation. The radiant heated pressure parts described are suitably connected into the boiler circulation system hereinafter described.

The convection heated pressure parts of the unit comprise a bank of steeply inclined steam generating tubes 20 extending between rows of vertical uptake and supply headers 21 and 22 respectively. The lowermost row of tubes 20 extends between the bottom end of the uptake headers 21 and a horizontal cross header 23 arranged below and connected to the supply headers 22 by nipples 24. Alternate tubes in this row are bent differently to form a slag screen to protect the remaining portion of the bank. A steam and water drum 25 is arranged transversely of and at a substantial distance above the tube bank 20 and forwardly spaced from the supply headers

22. A row of circulator tubes 26 starting at the top of the uptake headers 21 connects them to the steam space of the drum 25, while another row of circulator tubes 27 connects the water space of the drum to the cross header 23. Another row of tubes 28 extends vertically from the upper end of the supply headers 22 into a cross header 29 which is connected to the steam space of the drum 25 by tubes 30. The intertube spaces of the row of tubes 28 and nipples 24 are closed by refractory material to define a vertical baffle structure 31 forming with the row of supply headers 22 a continuation of the front side of the secondary furnace section to the header 29. The vertical portions of the downtake circulator tubes 27 also have their intertube spaces closed by refractory to define a wall 32 parallel to the baffle wall 31.

With the described construction the space enclosed by the tube bank 20, uptake circulators 26, drum 25, and downtake circulators 27 is divided by the baffle structure 31 into an upflow section 35, the sides of which form an extension of the secondary furnace section sides, and a downflow section 36 between the baffle 31 and the wall 32, the downflow section being substantially wholly at the front side of the headers 22. An inclined refractory baffle 37 extends downwardly from the lower portion of the baffle structure 31 in a plane spaced from the lower end of the wall 32 to provide a heating gas exit from the lower end of the downflow section 36 to an external air heater and stack connection. The portions of some of the circulator tubes 27 extending across the gas exit are bent out of a single row to provide space for the gas exit.

The portion of the setting occupied by the gas upflow and downflow sections is of substantial volume and advantageously employed for the location of the convection heated auxiliary fluid heating surface of the unit. The auxiliary fluid heating surface comprises serially connected vertically spaced banks of multiple-looped horizontally arranged superheater tubes 40 arranged in flat coils extending between superheater inlet and outlet headers 41 and 42 respectively, with the tube coils vertically arranged and extending from the uptake circulator tubes 26 to a point rearwardly of the tube row 28. The space between the forward ends of the superheater coils and the baffle structure 31 is employed as an upflow by-pass passage 35a for controlling the heat absorption of the superheater tubes as herein-after described. A row of tubes 44 extends inwardly and upwardly from the upper level of the supply headers 22 adjacent the forward ends of the superheater tube coils to a transverse header 45 arranged parallel to and spaced from the header 29. Tubes 46 extend vertically from the header 45 and then laterally to the steam space of the drum 25. The portions of the tubes 44 opposite the superheater tube coils have their intertube spaces closed by refractory to define a vertical baffle 47 extending from the header 45 to a point below the superheater tube bank and forming the rear side of the gas by-pass passage 35a and separating it from the main up-pass 35.

Steam generating units of the character described are designed for the production of high pressure superheated steam with steam temperatures approximately 950° F. at the superheater outlet header. The attainment of superheated steam temperatures of this value necessitates the presence of high temperature heating gases in contact with the superheater tubes with conse-

quent special problems of supporting and protecting the parts in this section of the unit. The by-pass passage 35a permits the amount of heating gases contacting with the superheater to be regulated. For this purpose one or more by-pass dampers 50 are movably mounted on the header 45 and arranged to extend over the top of the passage 35a to the header 29. The dampers 50 are externally operable in any suitable manner to control the amount of heating gases passing through the by-pass and consequently the amount passing over the superheater surface. To preserve the high thermal efficiency of the unit when the by-pass is in operation and also to prevent the control dampers 50 from becoming overheated, a pair of vertically spaced economizer sections 51 and 52 are positioned in the by-pass passage. Each of these economizer sections consists of a bank of vertical flat coils of multiple-looped nested horizontal tubes arranged side-by-side and extending transversely of the tube bank 20, and as shown in Fig. 9, corresponding coils of the sections are serially connected. The lower ends of the tubes in the section 51 are connected to an external inlet header 53, while the upper ends of the tubes in the section 52 are connected to an external outlet header 54, which in turn is connected to the water space of the drum 25. The arrangement of the economizer sections transversely of the tube bank permits the tube coils to be readily inspected and renewed through access openings in the side walls of the setting and simplifies the maintenance of the sections. It also permits the headers to be outside of the setting which would not be practicable otherwise.

The gas downflow section 36 contains the main economizer divided into three superposed vertically spaced sections 60, 61, and 62, each of which is formed by a series of horizontally extending multiple-looped vertical flat tube coils arranged side-by-side and extending in a direction transversely of the tube bank 20. Corresponding tube coils of adjacent banks are connected as herein-after described for a serial flow of water successively through the sections 60, 61, and 62 in the order named. The lower ends of the tubes in the section 60 are connected to an external inlet header 63, while the upper ends of the tube coils in the section 62 are connected to an external outlet header 64. Tubes 65 connect the header 64 to the inlet header 53 of the by-pass economizer sections. With this arrangement of counter-current flow of water relative to the heating gas flow is provided through the economizer sections 60, 61, and 62, with a parallel flow through the by-pass economizer sections 51 and 52 in the order named but in both the water flow is generally upward. A counter-current flow through the economizer sections 60, 61, and 62 is advantageous from the standpoint of thermal efficiency, while a parallel flow through the by-pass economizer sections 51 and 52 is advantageous in preventing the tube coils in that section from becoming steam-bound when steam is generated therein.

The described convection heated pressure parts are top supported from the external steel framework of the unit by means of U-shaped straps 66 surrounding the drum 25 and hangers 67 welded to the tubes 30, 46 and 26. The economizer sections 60, 61 and 62 are supported as shown in Figs. 2 to 7. The tubes of the section 60 are centrally supported from below on an I-beam 70 which extends between and is carried by a pair

of I-beams 71 extending through the side walls of the setting to the external steel work. The tube legs above the beam 10 are rigidly connected and supported from below by spacer members 72 welded to adjacent tube legs. The economizer section 60 is also supported from below at its opposite ends from the side walls of the setting, as shown in Figs. 6 to 8. The lowermost loop of each coil has a hook-shaped bracket 73 welded thereon and engaging a rod or bar 74 resting on spaced bracket members 75 welded at spaced points to a vertically extending channel member 76 incorporated in the corresponding side of the setting. The superjacent loops are supported from the bottom loop by dove-tail spacer connections 77, as shown in Figs. 6 and 8. Similar provisions are used for supporting the ends of the sections 61 and 62 from the sides of the setting.

The upper economizer sections 61 and 62 are centrally supported from below by the section 60 by the interconnecting tube portions, as shown in Figs. 4 and 5. The tube ends to be connected are joined by a coupling 78 and connected by slip hangers to the adjacent horizontally extending tube legs. Each slip hanger consists of an inner U-shaped lug 79 welded onto the curved portion of the tube and fitting around a pin 80 removably mounted in a pair of outer U-shaped lugs 81 welded onto the straight tube portion. With this arrangement the superjacent tube coils are centrally supported by tube portions acting as short columns under compression. The economizer supporting provisions described effectively maintain the economizer sections in their desired position, while permitting the looped ends of each tube coil to expand and contract as a whole relative to the end supports and independently of one another.

Special fluid cooled supports are provided for the by-pass economizer sections 51 and 52. As shown, each section is centrally supported from below by a group of tubes 85 extending at a slight inclination from a corresponding horizontally arranged header 86 at the front side of the wall 32 inwardly between the main economizer sections to a point beyond the tube row 44 turning upwardly parallel to the tubes 44 and 46 and then horizontally along the top of the setting to the steam space of the drum 25. The lower horizontal portions of the tubes 85 are supported on lugs 87 carried by the tubes 28 and 44, as shown in Figs. 10 and 11. The portions of the tubes 85 directly below each economizer tube coil are provided with tube supporting blocks 88 welded thereon on which the lowermost legs of the economizer section rest. The upper horizontal legs of the economizer tube coils are supported centrally from the lowermost leg by spacer blocks 72 similar to the spacers for the main economizer sections. Similar supporting tubes 89 are arranged to support the looped end portions of each economizer section. Superjacent looped portions of the economizer tubes are interconnected to one another by dove-tailed spacer blocks, as shown in Fig. 8. Each of the headers 86 is connected to the water space of the drum by tubes 90 to provide a fluid circulation through the corresponding supporting tubes 85 and 89. Support hangers 91 are connected to the upper ends of the vertical portions of the tubes 85 and 89 to transmit the load thereon to the external supporting steel work.

As shown in Figs 2 and 10 the forward end of each superheater tube coil has an expandible

supporting connection to the supporting tubes 44, 85, or 89. Each tube coil carries on its uppermost loop a hook member 93 engaging a bar 94 mounted on brackets 95 carried by adjacent supporting tubes. A similar arrangement is used at the opposite end of each superheater tube coil for expansibly supporting that end from the uptake circulator tubes 26. The subjacent tube legs of each superheater coil section are expansibly supported from the superjacent tube legs by slip hangers of the type shown in Fig. 5. With the described arrangement the superheater tube loops of each coil will be free to expand and contract as a whole relative to the supporting tubes and independently of one another.

While in accordance with the provisions of the statutes we have illustrated and described herein the best form of the invention now known to us, those skilled in the art will understand that changes may be made in the form of the apparatus disclosed without departing from the spirit of the invention covered by the claims, and that certain features of the invention may sometimes be used to advantage without a corresponding use of other features.

We claim:

1. A steam generator comprising a setting enclosing a bank of inclined steam generating tubes, an elevated steam and water drum, rows of uptake and downtime circulator tubes connecting the opposite ends of said tube bank to said drum, means forming baffles dividing the space defined by said tube bank, circulator tube rows and drum into a plurality of gas passes including a plurality of upflow passes above said steam generating bank and a downflow pass serially connected to said upflow passes at their upper ends and arranged beyond the downtime end of said steam generating bank, a bank of steam heating tubes extending across and confined to one of said upflow passes, a sectional economizer comprising a tube bank extending across only said downflow pass and a second tube bank serially connected thereto and extending across only the other upflow pass, flow control damper means for the last named upflow pass arranged above said second economizer tube bank, said economizer tube banks being arranged with the tubes thereof extending transversely of said steam generating tube bank, and means for supporting said economizer tube banks.

2. A steam generator comprising a setting enclosing a bank of inclined steam generating tubes, an elevated steam and water drum, rows of uptake and downtime circulator tubes connecting the opposite ends of said tube bank to said drum, means forming baffles dividing the space defined by said tube bank, circulator tube rows and drum into a plurality of gas passes including a wide upflow pass above the uptake end of said steam generating bank, a narrow upflow pass above the downtime end of said steam generating bank, and a downflow pass serially connected to said upflow passes at their upper ends and arranged laterally adjoining said narrow upflow pass beyond the downtime end of said steam generating bank, a bank of steam heating tubes extending across and confined to said wide upflow pass, a sectional economizer comprising a tube bank extending across only said downflow pass and a second tube bank serially connected thereto and extending across only said narrow upflow pass, flow control damper means for said narrow upflow pass arranged above said second economizer tube bank, said economizer tube bank being ar-

ranged with the tubes thereof extending transversely of said steam generating tube bank, and means for supporting said economizer tube banks.

3. A steam generator comprising a setting enclosing a bank of inclined steam generating tubes, a steam and water drum arranged a substantial distance above said tube bank, rows of uptake and downtake circulator tubes connecting the opposite ends of said tube bank to said drum, longitudinally spaced rows of vertically disposed fluid conduit elements having their lower ends connected to the lower end of said tube bank and their upper ends to said drum, means associated with said elements forming baffles dividing the space defined by said tube bank, circulator tube rows and drum into a plurality of gas passes including a wide upflow pass above the uptake end of said steam generating bank, a narrow upflow pass above the downtake end of said steam generating bank, and a downflow pass serially connected to said upflow passes at their upper ends and arranged laterally adjoining said narrow upflow pass beyond the downtake end of said steam generating bank, a bank of steam heating tubes extending across and confined to said wide upflow pass, a sectional economizer comprising a tube bank extending across only said downflow pass and a second tube bank serially connected thereto and extending across only said narrow upflow pass, flow control damper means for said narrow upflow pass arranged above said second economizer tube bank, said economizer tube banks being arranged with the tubes thereof extending transversely of said steam generating tube bank and said steam heating tube bank, and means for supporting said economizer tube banks.

4. A steam generator comprising a setting enclosing a bank of inclined steam generating tubes, an elevated steam and water drum, rows of uptake and downtake circulator tubes connecting the uptake and downtake ends of said tube bank respectively to said drum, means dividing the space defined by said tube bank, circulator tube rows and drum into a plurality of gas passes including a pair of upflow passes, a bank of steam heating tubes extending across one of said upflow passes, flow control damper means for the other upflow pass, an economizer tube bank in said other upflow pass below said damper means with the tubes thereof arranged transversely of said steam generating tube bank, and a plurality of supporting tubes extending across said other upflow pass below and supporting said economizer tube bank.

5. A steam generator comprising a setting enclosing a bank of inclined steam generating tubes, an elevated steam and water drum, rows of uptake and downtake circulator tubes connecting the uptake and downtake ends of said tube bank respective to said drum, means forming baffles dividing the space defined by said tube bank, circulator tube rows and drum into a plurality of gas passes including a pair of upflow passes and a laterally adjoining downflow pass serially connected to said upflow passes at their upper ends, a bank of steam heating tubes extending across one of said upflow passes, flow control damper means for the other upflow pass, an economizer tube bank in said other upflow pass below said damper means with the tubes thereof arranged transversely of said steam generating tube bank, and a plurality of supporting tubes extending across said downflow

pass and said other upflow pass below and supporting said economizer tube bank and having their opposite ends connected to said drum.

6. A steam generator comprising a setting enclosing a bank of inclined steam generating tubes, a steam and water drum arranged a substantial distance above said tube bank, rows of uptake and downtake circulator tubes connecting the uptake and downtake ends of said tube bank respectively to said drum, longitudinally spaced rows of vertically disposed fluid conduit elements having their lower ends connected to the lower end of said tube bank and their upper ends to said drum, means associated with said elements forming baffles dividing the space defined by said tube bank, circulator tube rows and drum into a plurality of gas passes including a pair of wide and narrow upflow passes and a laterally adjoining downflow pass serially connected to said upflow passes at their upper ends, a bank of steam heating tubes extending across and confined to said wide upflow pass, flow control damper means for said narrow upflow pass, a bank of multiple-looped economizer tubes in said narrow upflow pass below said damper means with the tubes thereof arranged transversely of said steam generating tube bank, and a plurality of supporting tubes extending across said downflow pass and said narrow upflow pass below and supporting said economizer tube bank and having their opposite ends connected to said drum.

7. A steam generator comprising a setting enclosing a bank of inclined steam generating tubes, a steam and water drum arranged a substantial distance above said tube bank, uptake and downtake circulator tubes connecting the opposite ends of said tube bank to said drum, longitudinally spaced rows of vertically disposed fluid conduit elements having their lower ends connected to the lower end of said tube bank and their upper ends to said drum, means associated with said elements forming baffles dividing the space defined by said tube bank, circulator tube rows and drum into a plurality of gas passes including a pair of upflow passes and a laterally adjoining downflow pass serially connected to said upflow passes at their upper ends, a bank of steam heating tubes extending across and confined to one of said upflow passes, a sectional economizer comprising a tube bank extending across only said downflow pass and a second tube bank extending across only the other upflow pass, flow control damper means for said other upflow pass arranged above said second economizer tube bank, said economizer tube banks being arranged with the tubes thereof extending transversely of said steam generating tube bank, means for supporting the ends of said first economizer tube bank at opposite sides of said setting, and a plurality of supporting tubes arranged below and supporting said second economizer tube bank and having their opposite ends connected to said drum.

8. A steam generator comprising a setting enclosing a bank of inclined steam generating tubes, a steam and water drum arranged a substantial distance above said tube bank, uptake and downtake circulator tubes connecting the opposite ends of said tube bank to said drum, longitudinally spaced rows of vertically disposed fluid conduit elements having their lower ends connected to the lower end of said tube bank and their upper ends to said drum, means associated with said elements forming baffles dividing the space defined by said tube bank, circulator tube rows and drum into a plurality of gas passes including

a pair of wide and narrow upflow passes and a laterally adjoining downflow pass serially connected to said upflow passes at their upper ends, a bank of steam heating tubes extending across and confined to said wide upflow pass, a sectional economizer comprising a tube bank extending across said downflow pass and a second tube bank extending across only said narrow upflow pass, flow control damper means for said narrow upflow pass arranged above said second economizer tube bank, said economizer tube banks being arranged with the tubes thereof extending transversely of said steam generating tube bank, means for supporting the ends of said first economizer tube bank at opposite sides of said setting, a beam support centrally of said first economizer tube bank, and a plurality of supporting tubes extending across said downflow pass and said narrow upflow pass below and supporting said second economizer tube bank and having their opposite ends connected to said drum.

9. In a steam generator comprising a setting enclosing a bank of inclined steam generating tubes, a steam and water drum, rows of uptake and downtake circulator tubes connecting the opposite ends of said tube bank to said drum, baffle means dividing the space defined by said tube bank, circulator tube rows and drum into a plurality of gas passes including an upflow pass and a laterally adjoining downflow pass serially connected to said upflow pass at their upper ends, a bank of steam heating tubes extending across said upflow pass, and a bank of horizontally arranged multiple-looped economizer tubes arranged in said downflow pass transversely of said steam generating tube bank and circulator tube rows with their looped portions within said downflow pass, the improvement which comprises means for slideably supporting the looped portions of said economizer tube bank from said setting at opposite sides of said setting and independently of said circulator tubes, and a beam support arranged centrally below said economizer tube bank.

10. In a steam generator comprising a setting enclosing a bank of inclined steam generating tubes, a steam and water drum, rows of uptake and downtake circulator tubes connecting the opposite ends of said tube bank to said drum, baffle means dividing the space defined by said tube bank, circulator tube rows and drum into a plurality of gas passes including an upflow pass and a laterally adjoining downflow pass serially connected to said upflow pass at their upper ends, a bank of steam heating tubes extending across said upflow pass, and a plurality of vertically spaced serially connected banks of multiple-looped economizer tubes horizontally arranged in said downflow pass transversely of said steam generating tube bank, the improvement which comprises a center beam support for the lowermost economizer tube bank and beam support.

5 most economizer tube bank, and means including rigid tubular connectors providing a flow connection between corresponding tubes of said economizer tube banks arranged to transmit the center load of an upper economizer tube bank to said lowermost economizer tube bank and beam support.

11. In a steam generator comprising a setting enclosing a bank of inclined steam generating tubes, a steam and water drum, rows of uptake and downtake circulator tubes connecting the opposite ends of said tube bank to said drum, baffle means dividing the space defined by said tube bank, circulator tube rows and drum into a plurality of gas passes including an upflow pass and a laterally adjoining downflow pass serially connected to said upflow pass at their upper ends, a bank of steam heating tubes extending across said upflow pass, and a plurality of vertically spaced serially connected banks of multiple-looped economizer tubes arranged in said downflow pass transversely of said steam generating tube bank, the improvement which comprises means for supporting said economizer tube banks at opposite sides of said setting, a center beam support for the lowermost economizer tube bank, and means including rigid tubular connectors providing a flow connection between corresponding tubes of said economizer tube banks arranged to transmit the center load of an upper economizer tube bank to said lowermost economizer tube bank and beam support.

12. In a fluid heater comprising a setting enclosing a pass for the passage of heating gases, a plurality of vertically spaced serially connected banks of multiple-looped fluid heating tubes horizontally arranged in said pass, a center beam support for the lowermost tube bank, and means including rigid tubular connectors providing a flow connection between corresponding tubes of vertically adjacent tube banks arranged to transmit the center load of an upper bank to said lowermost bank and beam support.

13. In a fluid heater comprising a setting enclosing a pass for the passage of heating gases, a plurality of vertically spaced serially connected banks of multiple-looped fluid heating tubes horizontally arranged in said pass with substantially all of their looped portions within said pass, means for slidably supporting the looped portions of said tube banks at opposite sides of said setting, a center beam support for the lowermost tube bank, and means including rigid tubular connectors providing a flow connection between corresponding tubes of vertically adjacent tube banks arranged to transmit the center load of an upper bank to said lowermost bank and beam support.

DANA H. N. MAYO.
ARTHUR E. RAYNOR.
